ROTARY CUTTER

Joseph Ciarlane, Fitchburg, Mass.

Application November 25, 1938, Serial No. 242,333

2 Claims. (Cl. 146—189)

This invention relates to a cutter rotatable with a shaft which carries it and used ordinarily for cutting meat into small particles for use as hamburg steak, and the like.

The principal objects of this invention are to provide such a rotary cutter with a series of blades fixedly but detachably secured and adjustable; to provide each blade with an integral portion constituting another blade so that if there are four of the first named blades, there will be eight blades altogether; to provide the second blade preferably parallel with the next blade in the series, and to provide these blades all at the same angle to the flat face of the hub of the cutter so that they will cut uniformly, and to provide a convenient means for removing two blades at a time from the cutter head.

Other objects and advantages of the invention will appear hereinafter.

Reference is to be had to the accompanying drawing, in which

Fig. 1 is a diametrical sectional view of a meat cutting or chopping machine, illustrating this invention;

Fig. 2 is a rear elevation of the cutter head;

Fig. 3 is a front elevation of the same, showing the blades;

Fig. 4 is an edge view taken in the direction of the arrow 4 in Fig. 3;

Fig. 5 is a front view of a part of the cutter head with the blades removed;

Fig. 6 is a sectional view on enlarged scale on the line 6—6 of Fig. 3;

Fig. 7 is a perspective view of one of the blade elements which involves two blades, on enlarged scale, and

Fig. 8 is a sectional view on the line 8—8 of Fig. 3 showing how a blade can be removed.

This cutter is an improvement on the ordinary rotary head for the blades. This head 10 is mounted on a shaft 11 which also carries the feed screw 12. The blades on the head 10 engage a perforated plate 13 through which the meat is forced, all this being located in the casing 14. In this case the shaft 11 is provided with a square portion 15 located in a square hub 16, which constitutes the means for securing it to the shaft to and transmitting the rotation of the shaft to the blades.

The hub 15 is integral with a knife carrier 17. This knife carrier it will be observed, is provided with four radial arms 18 projecting from the corners of the hub 16 and on these radial arms are arms 19 in each case which project parallel to the next arm. On the cutting side of the knife

the arms 18 and 19 are provided with kerfs or grooves 20 and 21. These grooves are arranged at an angle to the plane of that side of the knife carrier and both sets of them at the same angle, which may be approximately 20°. That is, they 5 slant in the direction in which the cutter is to rotate. At the back of each groove 20 is a short depression 22 which can be a continuation of the groove 21 but is used for removal of the knives, as will appear hereinafter.

Each knife is formed with a main part 23 and a right angular part 24. Each one is provided with a sharpened edge at the outside portion, both of the sharpened edges of the knives 23 and 24 being in the same plane as that of the rest of 15 the knives. Each knife also is provided with an opening 25 which, when the knife is in place, will register with the groove 22.

It will be obvious, of course, that four of these double knives are inserted in the four double 20 grooves 20—21 so that the cutter will assume the condition shown in Figs. 3 and 4. In this way it will be seen that these cutters all slant and although one set is at right angles to the other set, they all slant forwardly and practically equally. 25 The knives are easily put in place in the cutter support and are fixed therein by being driven into the grooves 20 and 21. On account of the fact that an integral T-shaped knife is driven into a T-shaped groove, both at an angle to the plane 30 of the holder, they will be gripped in the grooves firmly and will not get out of place easily. As a matter of fact the knife, being held up against the perforated plate 13, is held firmly in that position. There is nothing to cause these knives 35 to be loosened unless the nut 26 happens to become loosened, which is not likely.

By this means a double quantity of knives is provided in the same area as has been used before, they are held in position very firmly and 40 they perform the work required approximately twice as fast. They are arranged in pairs around the cutter head and held in place by the perforated plate. The slant of the blades keeps them in sharpened condition for a long time on 45 account of working against this flat perforated plate.

When it is desired to take the cutter out and remove the blades, a tool 27 is employed which enters the groove 22 and the perforation 25 in 50 the knife, releases the knife very readily, and allows it to be removed. Of course, instead of a perforation, it could be replaced by a notch extending inwardly from the bottom.

Having thus described my invention and the 55

advantages thereof, I do not wish to be limited to the details herein disclosed, otherwise than as set forth in the claims, but what I claim is:

- 5 1. A rotary cutter for a meat grinding machine having a square hub for fitting on a square part of the operating shaft and provided with four radial projections from the corners of said square hub, each projection having in the plane thereof a radial groove extending from the corner of said hub and slanted to a material angle from the plane of the face of the cutter and provided with an equal number of series of intersecting grooves extending at right angles to said first named grooves and a series of four blades fitting in the first named radial grooves, each blade having an integral cutting portion fitting in the second set of grooves, the second series of grooves extending inwardly at the same angle, so that both sets of four blades each will be located at 10 the same angle to the face of the cutter.
- 15
- 20

2. A rotary cutter for a meat grinding machine having a polygonal hub for fitting on a polygonal part of the operating shaft and provided with radial projections from the corners of said hub, each projection having in the plane thereof a 5 radial groove extending from the corner of said hub and provided with an equal number of intersecting grooves extending at equal angles to said first named grooves, a groove in each case on opposite sides of the first named groove extending to the opposite end of the arm, and a series of blades fitting in the first named radial grooves, each blade having an integral portion fitting in the second set of grooves, the first set of blades each having an opening therethrough 10 on the side opposite the second set of blades, and the corresponding projections each having a further groove alining with each of said holes, for receiving a tool, for releasing the blades.
